UNITED STATES PATENT OFFICE.

JAMES E. DILLON, OF MASONTOWN, PENNSYLVANIA.

PROTECTIVE DEVICE FOR ELECTRICALLY-OPERATED MINING MACHINES AND THE LIKE.

Application filed February 12, 1927. Serial No. 167,803.

This invention relates to protective devices for electrically operated mining machines and the like which are not permanently connected with the negative side of 5 a grounded circuit.

An important object of the invention is the provision of a control for these machines, such that upon break down or failure of the insulation on wires, armatures, coils, 10 controller, rheostat or cable reel, the circuit to the motor is broken and cannot be restored except by a manual operation which, provided the break down has not been repaired, will be inoperative.

15 A further object of the invention is to provide a control system of this character which includes means whereby the cable reel upon which the feed cables, by means of which such machines are supplied, are 20 wound, is at all times, during operation of the machine or during idle periods when the machine is still connected with the supply current, grounded, so that in event of a break down of the insulation of the feed 25 wire wound thereon, the circuit is broken by blowing of the fuse of the positive feed wire.

A still further object of the invention is to produce a control of this character which 30 embodies means automatically interrupting the circuit in event the feed wires are improperly connected with either the source of supply or the machine.

These and other objects I attain by the 35 construction shown in the accompanying drawing, wherein the figure is a diagram illustrating a control constructed in accordance with my invention and its connections to the machine.

40 Referring now more particularly to the drawing, the numeral 10 generally designates the usual cable reel, upon which positive and negative feed wires 11 and 12 supplying the machine are wound. 13 designates the motor and 14 the metallic frame 45 of the machine. The circuit of the motor M is interrupted between stationary contacts 15 and 16 and coacting movable contacts 17 and 18 carried by the armature 19 of a main control coil 20. The circuit is, of 50 course, likewise interrupted by placement of the controller arm 21 of a rheostat R in the "off" position.

The contacts 15 and 16 are directly connected with the positive and negative feed

wires by wires 22 and 23 which are connected by a shunt 24 including the coil 25 of a reverse current relay, the contacts of which are indicated at 26 and 27. These contacts are connected to the negative wire 60 23 and to one terminal of the coil 20 respectively. The contact 27 is also connected to one contact 28 of a pair of contacts 28 and 29 with which the contacts 17 and 18 engage when the coil 20 is de-energized. 65 The contact 29 is electrically connected to the frame of the cable reel by a wire 30. The negative wire 23 includes the coil 31 of a series relay, the armature of which coacts with the contacts 32 and 33 which are connected to the wire 30 and wire 23 respectively. When the motor circuit is closed, the circuit between the contacts 32 and 33 is closed connecting the negative wire 23 to the reel frame. 75

The controller arm 21 supports an insulated contact element 34, which, when the controller arm is coacting with any of the contacts of the rheostat, electrically connects a pair of contacts 35 and 36. The contact 35 is connected to the positive wire 22, while the contact 36 is connected with one contact 37 of a pair of contacts 37 and 38. The contact 38 is connected to the second terminal of the coil 20. The contacts 37 and 80 38 form a portion of the ground relay, the coil 39 of which is connected to the motor circuit between the contact 18 and the motor 13 and is connected to the frame 14 of the machine. 90

The insulated support associated with the motor arm likewise includes a contact element 40, which, when the controller is in the "off" position, electrically connects a pair of contacts 41 and 42 connected to the controller arm 21 and the connection between the motor 13 and contact 18 respectively. The armature 19 of the main control coil 20, when the coil is de-energized, places the contacts 17 and 18 in engagement 95 with the contacts 28 and 29. The armature of the coil 25, when energized, provided the current is properly fed to the machine, closes upon the contacts 26 and 27 electrically connecting the same. 100

105 The operation is as follows:—If the leads 11 and 12 are properly connected and are properly connected to the wires 22 and 23 and the controller arm 21 is in the "off" position, the contacts 17 and 28 and 18 and 110

29 remain in engagement with one another. The negative wire 23 is connected to the contacts 26, 27, 28 and 17, the controller arm, contacts 18, 29 and wire 30 with the reel frame, so that if there exists any break down of insulation, causing grounding of the positive wire 22 at the reel, a blow-out of the fuse of the positive feed wire 11 will occur. When the controller arm is moved 10 to the "on" position, the contact 34 connects the contacts 35 and 36, with the result that a circuit is established from the positive wire 22 through the contacts 35, 34 and 36, contacts 37 and 38, coil 20; contacts 27 and 26 to the negative feed wire. The coil 20 being energized, the armature 19 is attracted connecting the contacts 15 and 16 to the contacts 17 and 18 and completing the motor circuit.

20 It will be noted that the circuit of the motor is controlled through the ground relay and in event at the time the motor circuit is established there is a break down of insulation, permitting positive current 25 to flow to the frame 14 of the machine, a circuit will be established from this frame through the coil 39, contacts 18 and 16 to the negative wire 23. This will attract the armature of the ground relay, breaking the 30 circuit of the coil 20 between the contacts 37 and 38, thereby causing the armature 19 to move to open position where its contacts 17 and 18 engage the contacts 28 and 29. The armature 43 of the ground circuit 35 relay includes an extension 44 in the form of a rack bar, coating with a pawl 45, which serves to retain the armature in its open circuit position until it is moved to the closed circuit position by a manual operation. If this manual operation is effected 40 and the break has not been repaired, a second attempt to move the control arm 21 to its "on" position will have the same result. It will be noted that at all times when the 45 motor circuit is complete, the armature of the coil 31 has closed upon the contacts 32 and 33, connecting the reel frame in the negative circuit to replace the connection broken by the movement of the armature 50 19.

Since the control mechanism hereinbefore described is capable of a certain range of change and modification without materially departing from the spirit of the invention, 55 I do not limit myself to such specific structure except as hereinafter claimed.

I claim:—

1. In a safety system for electrical motor 60 operated machines the frames of which are not, permanently connected to the negative side of a grounded circuit, a normally open circuit for the motor including a rheostat, positive and negative feed wires for the motor circuit, a reel upon which the feed 65 wires are wound, a control circuit including

means for closing the motor circuit operative only when the rheostat controller arm is in "on" position, parallel connections between the negative side of the motor circuit and the reel frame, one of which is nominally open and the other of which is nominally closed, said means when the motor circuit is open closing the open connection and means opening the other of the connections when the motor circuit is closed. 70

2. In a safety system for electrical motor operated machines the frames of which are not permanently connected to the negative side of a grounded circuit, a normally open circuit for the motor including a rheostat, 80 positive and negative feed wires for the motor circuit, a reel upon which the feed wires are wound, a control circuit including an electro-magnet switch for closing the motor circuit operative only when the rheostat controller arm is in "on" position, 85 parallel connections between the negative side of the motor circuit and the reel frame, one of which is normally open and the other of which is normally closed, said switch having a back contact which when the motor circuit is open closes the open connection and a series relay in the negative side of the motor circuit for opening the other of the connections. 95

3. In a safety system for electrical motor operated machines the frames of which are not permanently connected to the negative side of a grounded circuit, a normally open circuit for the motor including a rheostat, 100 a control circuit including means for closing the motor circuit operative only when the rheostat controller arm is in "on" position, means for opening the control circuit if the frame of the machine is positively 105 charged and manually releasable means for retaining the last named means in open circuit position and means for rendering said circuits inoperative upon a reversal of the feed connections to the machine. 110

4. In a safety system for electrical motor operated machines the frames of which are not permanently connected to the negative side of a grounded circuit, a normally open circuit for the motor including a rheostat, 115 a control circuit including means for closing the motor circuit operative only when the rheostat controller arm is in "on" position, means for opening the control circuit if the frame of the machine is positively 120 charged, manually releasable means for retaining the last named means in open circuit position and a reverse current relay rendering all of said circuits inoperative upon a reversal of the feed connections to 125 the machine.

In testimony whereof I hereunto affix my signature.

JAMES E. DILLON.
